PROCESS OF PRODUCING ALUMINUM NITRID.

1,241,834.

Specification of Letters Patent.

Patented Oct. 2, 1917.

Continuation in part of application Serial No. 587,419, filed October 17, 1910. This application filed October 12, 1916. Serial No. 125,158.

To all whom it may concern:

Be it known that I, HARRY L. DUNCAN, a citizen of the United States, now residing at Mahwah, Bergen county, New Jersey, have made a certain new and useful Invention Relating to Processes of Producing Aluminum Nitrid, of which the following is a specification, taken in connection with the accompanying drawing, which forms part 10 of the same. This application is a continuation in part—that is, contains subject-matter taken from my copending application 587,419, filed October 17, 1910.

This invention relates especially to processes for producing nitrids of aluminum and other metals by supplying the hot carbonaceous aluminous charge of material, for instance, to a rotating treating kiln through which it is gradually fed and simultaneously 20 agitated. The material may be heated by a centralized luminous flame within the kiln which may be produced by supplying to the discharge end of the kiln a low pressure diffuse heating jet or stream of luminous 25 flame producer gas and injecting substantially axially into the kiln a high pressure jet of air or other oxidizer, engaging said heating stream and forming therewith a substantially centralized heating flame 30 transmitting heat to the kiln walls and material, while kept from undesirable contact therewith by the layer of dead wall gases in engagement with the kiln walls and material. A nitrogenous treating jet of hot 35 producer gas may be injected into the kiln so as to impinge on the falling agitated charge of material and convert the same without exerting undesirable action on the kiln walls and for this purpose the jet may 40 be of high pressure and discharged from a flattened nozzle substantially in line with the bank of material. A nitrogenous reducing atmosphere is preferably maintained in the lower end of the treating kiln at a slight 45 excess of pressure above the outside air to minimize ingress thereof and the combustible gases discharged from the treating kiln may be used to heat the charge of material as by burning them in a preheating kiln.

An illustrative form of apparatus for carrying out this process is shown in a somewhat diagrammatic way in the accompany-

ing drawing in which Figure 1 is a vertical section and Fig. 2 a transverse section through the treating kiln taken substantially along the line 2—2 of Fig. 1. The treating rotary kiln 1 may be provided with refractory, preferably inert, lining 32 of any suitable material and with a constricted discharge throat 2, the kiln being mounted and rotated in any desired way. The hood 3, with which the discharge end of the kiln co-operates, is preferably tightly connected therewith, a suitable flange 4 being if desired, provided on the shell of the kiln and 55 co-operating with suitable metallic or other packing rings, washers or members 5 secured to the hood so as to make a tight kiln joint. The upper end of the kiln which may, as indicated, be of the bottle-neck type, may be 60 similarly connected with the housing 6 through the flange 7 and packing washers or connections 8. The kiln gases from this treating kiln 1 may be discharged through the port 9 after passing up through the 65 passage 10 in the housing and the combustible elements of these kiln gases may be burned in a suitable rotary preheating kiln 11, preferably provided with a constricted discharge throat 12 and mounted and rotated in any desired way. The upper end of this kiln may co-operate with a suitable stack chamber 14 and stack 15 of sufficient height to maintain the desired stack draft through the kiln and draw in additional air through 75 the usual kiln joint 16 which promotes the heating action in this kiln. The material discharged from this preheating kiln preferably slides past a swinging gate 19 mounted on the support 18 and preventing 80 leakage of gas from the passage 10. Suitable air injecting pipes 20 may be arranged within the port 9 and supplied with air at the desired pressure by a suitable fan or blower 23 connected with these pipes 20 through the regulating valves 21, 22. In this way the velocity of the kiln gases passing through the port 9 into the preheating kiln 11 may be increased to the desired extent and combustion in the kiln correspondingly promoted.

The alumina, bauxite or other material may be fed from the hopper 24 into the preheating kiln by a suitable screw conveyor 26.

arranged in the casing 25 and operated at the desired speed by the pulley 27. The aluminous material is gradually fed down the preheating kiln by its rotation and becomes quite highly heated therein so as to be hot when discharged into the treating kiln 1. Additional carbonaceous material may be conveniently incorporated with the charge entering the treating kiln by feeding such pulverized carbon or the like from the hopper 28 and connected conveyer casing 29 by the feed screw 30 driven at the desired speed by the pulley 31. This carbonaceous material thus becomes mixed with the aluminous portion of the charge as the materials enter the treating kiln and becomes intimately mingled therein as they are continually agitated and simultaneously fed down through the kiln in the form of an inclined bank of material on its ascending side. The material entering the treating zone at the lower end of the kiln is thus substantially homogeneous and has been still more highly heated in the upper part of the treating kiln.

It is desirable to maintain within the treating kiln a nitrogenous reducing atmosphere which may be conveniently done by supplying to the kiln ordinary producer gas which contains large proportions of nitrogen and of carbon-monoxid. By supplying such producer gas to the lower end of the treating kiln in sufficient amounts, a slight excess of pressure may be maintained within the kiln above that of the outside air which tends to prevent air being drawn into the kiln through the various openings in the hood. A treating jet of such nitrogenous gas is also preferably injected into the discharge end of the kiln in such way as to impinge on the falling agitated charge of material and effect the desired reactions therein, which of course develop considerable heat where aluminum nitrid is formed. It is desirable to inject the treating gas in the form of a flat treating jet having its flat side substantially in line with the bank of material extending up through the kiln so as to impinge upon the material throughout a considerable treating zone without exerting undesirable action on the kiln walls which may with good results be coated with a protective layer of the forming material. This flattened treating jet 35, may as indicated, be discharged at an angle of some thirty degrees or so to the adjacent kiln walls or bank of material on which it impinges, and this gas jet may be discharged from a suitable nozzle 36 in the hood connected with a pipe 37 leading from the producer 39 and provided with a regulating valve 38 so that the hot treating gases may be supplied at the desired high pressure. This producer should, of course, be operated so as to secure a sufficiently high temperature in the

treating jet to definitely effect the desired chemical reactions in the material in the kiln and for this purpose the producer may be blown with air without the use of steam or similar cooling means and the producer gas may of course be still more highly heated by well known regenerator or other heating devices before injecting it into the kiln. In order to preliminarily heat the treating kiln and maintain it and the material fed therethrough at the desired high temperature, a luminous heating flame may with advantage be employed, preferably in a substantially centralized position within the kiln so as to transmit heat by radiation to the material and kiln walls without destructive action thereon, and thus supply at least a large part of the heat required to bring the charge up to the combining temperature, although if desired additional heat can of course be supplied as by electric heating elements arranged in the kiln walls for instance. A substantially centralized jet of air or other oxidizing material together, if desired, with suspended particles of oil, powdered coal or other fuel for combustion therewith may be injected into the kiln by any suitable injecting devices so as to produce in this way a luminous heating flame which is kept substantially or largely out of contact with the kiln walls or material because of the interposed reducing atmosphere in the kiln. If desired, a suitable high pressure air jet may be substantially axially injected into the kiln to burn in the reducing atmosphere therein and transmit heat to the kiln walls and material without undesirable contact therewith. For some purposes it is desirable to supply to the kiln in connection with such air jet a diffuse low pressure jet or stream of luminous flame producer or other gas. Such a low pressure heating stream of gas may be injected through the flaring gas port 46 connected with the pipe 47 from the producer 49 and having the controlling valve 48 therein. This producer is preferably operated to give luminous flame gas which may be enriched by incorporating hydrocarbon oils or similar material therewith. A high pressure directive air jet may be injected into the kiln along the line 50 through the air nozzle 51 supplied with air from the fan or blower 43, the pressure or velocity of the issuing jet being regulated by the valve 52 so as to be in the neighborhood of one to two ounces equivalent pressure on entering the kiln so as to give the resulting flame a sufficiently centralized position. The rough kiln walls tend to hold practically stationary the layer of gases in contact with them so that these dead wall gases tend to prevent undesirable contact between the heating flame, preferably of highly luminous character, and the kiln walls and material. Another air jet

may be injected into the kiln for initially heating the same through the nozzle pipe 41 connected to the fan or blower 43 and supplied with air at the desired pressure and in the proper amounts through the regulating valve 42. This heating jet is adapted to cooperate with the gas passing through the nozzle 36 which is provided with a relieved portion 40 at its upper discharge end and under these conditions the gas pressure should be sufficiently low so as to inject through this nozzle a diffuse gas jet and prevent such forcible impingement upon the material as occurs under normal working conditions.

The treating kiln may be put in operation by admitting sufficient producer gas thereto to substantially displace the air therein and then preferably supplying luminous flame producer gas to the kiln in sufficient amounts so as to produce luminous heating flame therein in connection with the air jets. These jets may be ignited in any desired way as by the electric igniter 56 which may be inserted through a suitable opening 54 so as to bring the sparking terminals 55 adjacent the air jet to cause ignition when high tension electricity is passed through the wires 57. A suitable bushing 58 of course normally closes the opening 54 around this igniter and the opening is kept closed during the normal operation of the kiln, preferably by a door having a transparent window or peep hole to allow observation of the kiln interior. The heating flame produced under these conditions may have the shape and location indicated as 45 and the layer of dead wall gas 61 tends to prevent contact between this flame and the kiln walls or material. When the material has been sufficiently heated the nitrogenous reducing gases in the kiln react with the aluminous carbonaceous charge forming nitrid and this action may be promoted by injecting the treating jet 35 of nitrogenous producer gas into engagement with the agitated material. This promotes the formation of a highly heated treating zone in the lower end of the kiln so that the conversion of the material passing therethrough is effected to the desired extent before this material 60 is discharged through the chute 33 and passed through the swinging discharge gate 34 which maintains a substantial closure at the lower end of this chute.

Having described this invention in connection with a number of illustrative forms of apparatus, elements, arrangements and steps, to the details of which disclosure the invention is not of course to be limited, what is claimed as new and what is desired to be secured by Letters Patent is set forth in the appended claims.

1. The process of producing aluminum nitrid which consists in continuously sup-

plying the hot carbonaceous aluminous charge of material to a rotating treating kiln, in agitating and feeding said charge through said kiln in the form of an inclined bank of material, in supplying through the discharge end of said kiln a low pressure diffuse heating stream of luminous flame producer gas, in injecting substantially axially into said kiln a high pressure jet of air engaging said heating stream and forming therewith a luminous substantially centralized heating flame kept from undesirable contact with the material and kiln walls by the dead wall gases while transmitting heat thereto, in maintaining in the lower end of said kiln a nitrogenous reducing atmosphere at a pressure above that of the outside air, in injecting through the discharge end of said kiln a flattened high pressure nitrogenous treating jet of hot producer gas to impinge on the falling agitated charge of material and convert the same into nitrid without exerting undesirable action on the kiln walls and in burning the combustible gases discharged from said kiln to heat the charge of material supplied thereto.

2. The process of producing aluminum nitrid which consists in supplying the carbonaceous aluminous charge of material to a rotating treating kiln and thereby agitating and feeding said charge through said kiln, in supplying through the discharge end of said kiln a low pressure diffuse heating stream of luminous flame producer gas, in injecting substantially axially into said kiln a high pressure jet of air engaging said heating stream and forming therewith a luminous substantially centralized heating flame transmitting heat to the material and kiln walls, in maintaining in the lower end of said kiln a nitrogenous reducing atmosphere and in injecting through the discharge end of said kiln a flattened high pressure nitrogenous treating jet of hot producer gas to impinge on the material and convert the same into nitrid without exerting destructive action on the kiln walls.

3. The process of producing metallic nitrid which consists in supplying the carbonaceous charge of material to a rotating treating kiln and thereby agitating and feeding said charge through said kiln, in supplying through the discharge end of said kiln a low pressure diffuse heating stream of producer gas, in injecting substantially axially into said kiln a jet of air engaging said heating stream and forming therewith a substantially centralized heating flame transmitting heat to the material and kiln walls, in maintaining a nitrogenous reducing atmosphere in the lower end of said kiln and in injecting a high pressure treating jet of hot producer gas into said kiln to impinge on the material therein and convert the same into nitrid.

without exerting destructive action on the kiln walls.

4. The process of producing metallic nitrid which consists in supplying the carbonaceous charge of material to a treating kiln, in agitating and feeding said charge through said kiln in the form of a bank of material, in injecting into said kiln a flattened high pressure nitrogenous treating jet of combustible 10 gas to impinge on the agitated bank of material and convert the same into nitrid without exerting destructive action on the kiln walls and in injecting into said kiln a jet of air engaging said treating gas and forming therewith a heating flame transmitting heat to said material and kiln walls without undesirable action thereon.

5. The process of producing metallic nitrid which consists in supplying the charge containing reducing material to a treating kiln, in agitating and feeding said charge through said kiln in the form of a bank of material, in injecting a narrow nitrogenous treating jet into impingement with the agitated 20 charge of material to convert the same into nitrid without exerting undesirable destructive action on the kiln walls, in maintaining a nitrogenous reducing atmosphere in the lower part of said kiln and in heating said material.

6. The process of producing metallic nitrid which consists in supplying the charge containing reducing material to a treating kiln, in agitating and feeding said charge through 35 said kiln in the form of a bank of material, in injecting a hot small area nitrogenous treating jet into impingement with the agitated charge of material to convert the same and in maintaining a nitrogenous reducing atmosphere about said charge of material in the discharge end of said kiln.

7. The process of producing aluminum nitrid which consists in supplying the carbonaceous aluminous charge of material to a 45 treating kiln, in agitating and feeding said charge through said kiln in the form of a bank of material, in injecting a narrow nitrogenous treating jet into impingement with the agitated charge of material to convert 50 the same without exerting undesirable destructive action on the kiln walls, in maintaining a reducing atmosphere in contact with said converted material at the discharge end of said kiln and in injecting an 55 oxidizing jet into said kiln to form a heating flame therein transmitting heat to the material and kiln walls without undesirable action thereon.

8. The process of producing aluminum nitrid which consists in agitating the charge of material in a treating kiln, in maintaining a nitrogenous reducing atmosphere in contact with said material at one end of said kiln, in injecting into said kiln an oxidizing jet to form a heating flame in said 60

kiln transmitting heat to said material without destructive action thereon and in injecting a jet of nitrogenous treating gas into impingement with said charge of material to convert the same into aluminum nitrid.

9. The process of producing aluminum nitrid which consists in supplying the carbonaceous charge of material to a rotating treating kiln and thereby agitating and feeding said charge through said kiln, in supplying combustible nitrogenous treating gas to the discharge end of said kiln to maintain therein a nitrogenous reducing atmosphere at a pressure at least equal to that of the adjacent outside atmosphere, in injecting 75 substantially axially into said kiln a jet of air engaging said gas and forming therewith a substantially centralized luminous heating flame transmitting heat to the material and kiln walls without undesirable 80 contact therewith and in bringing said material while highly heated into engagement with said nitrogenous treating gas to convert the same into aluminum nitrid.

10. The process of producing aluminum 90 nitrid which consists in supplying the charge containing reducing material to a treating kiln, in agitating and feeding said charge through said kiln in the form of a bank of material, in injecting a narrow nitrogenous 95 treating jet into impingement with the agitated charge of material to produce nitrid therein without exerting undesirable destructive action on the kiln walls, in maintaining a nitrogenous reducing atmosphere 100 in the lower part of said kiln and in heating said material.

11. The process of producing aluminum nitrid which consists in agitating and feeding the charge of aluminous material 105 through a rotating treating kiln, in maintaining a nitrogenous reducing atmosphere in contact with said material in the treating zone of the kiln, in supplying heat to the material from a substantially centralized 110 luminous flame in the kiln, in injecting a high pressure jet of hot nitrogenous gas to impinge on the heated material in said treating zone at an angle of more than fifteen degrees to the adjacent kiln walls to 115 convert the material into aluminum nitrid and in preventing substantial ingress of oxidizing gases into the lower end of the kiln adjacent the kiln walls or material.

12. The process of producing aluminum 120 nitrid which consists in agitating and feeding the charge of aluminous material through a rotating treating kiln, in maintaining a nitrogenous reducing atmosphere in contact with said material in the treating 125 zone of the kiln, in supplying heat to the material from a substantially centralized luminous flame in the kiln and in injecting hot nitrogenous gas to impinge on the heated material in said treating zone at an angle 130.

of more than fifteen degrees to the adjacent kiln walls to convert the material into aluminum nitrid.

13. The process of producing aluminum nitrid which consists in agitating and feeding the charge of aluminous material through a rotating treating kiln, in maintaining a nitrogenous reducing atmosphere in contact with said material in the treating zone of the kiln, in supplying heat to the material and in injecting hot nitrogenous gas to impinge on the heated material in said treating zone at an angle of more than fifteen degrees to the adjacent kiln walls to convert the material into aluminum nitrid.
14. The process of producing aluminum nitrid which consists in agitating and feeding a charge of aluminous material through a rotating treating kiln, in producing luminous heating flame in said kiln to radiate heat to the kiln walls and material, without undesirable contact therewith, in maintaining a nitrogenous reducing atmosphere in contact with the heated material in the treating zone of the kiln and in injecting a jet of hot nitrogenous gas into said kiln to impinge on the heated material in the treat-

ing zone at an angle of at least as much as twenty degrees to the adjacent kiln walls to convert the material into aluminum 30 nitrid.

15. The process of producing aluminum nitrid which consists in maintaining a nitrogenous reducing atmosphere in contact with the aluminous material in the treating 35 zone, in supplying heat to the material and in injecting a high pressure jet of hot nitrogenous gas to impinge on the heated material in said treating zone at an angle of more than twenty degrees to convert the 40 material into aluminum nitrid.

16. The process of producing aluminum nitrid which consists in maintaining a nitrogenous reducing atmosphere in contact with the aluminous material in the treating zone, in supplying heat to the material and in injecting nitrogenous gas to impinge 45 on the heated material in said treating zone to convert the material into aluminum nitrid.
